Application May 15, 1946; Serial No. 669,803

4 Claims. (Cl. 200—46)

1

This invention presents a mechanism for selectively closing and opening electric circuits which has been devised to be especially useful as a station selector for radio receivers.

An object of the invention is to provide a mechanism for closing and opening electric circuits which will be of novel and improved construction.

A further object is to provide a station selector for radio receivers wherein will be incorporated various desirable and improved features and characteristics of construction novel both as individual entities of said selector and in combination with each other.

A further object is to provide a station selector for radio receivers which can be constituted as an entity adapted to be associated in novel and improved manner with radio receivers now of commerce.

And a further object is to provide a station selecting mechanism for radio receivers as herein-after set forth.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible so long as within the spirit of the invention and the scope of the claims which follow.

In the accompanying drawings forming a part of this specification,

Fig. 1 is a perspective view disclosing a radio receiver and a station selector, or mechanism for selectively closing and opening electric circuits, made according to the invention and associated with said radio receiver;

Fig. 2 is a block diagram disclosing the basic circuit of a superheterodyne radio receiver and also disclosing circuits of the station selector of the invention associated with said basic circuit;

Fig. 3 is an enlarged vertical longitudinal sectional view of the station selector of Fig. 1, taken as on line 3—3 in Fig. 4, parts being omitted;

Fig. 4 is a horizontal longitudinal sectional view, taken as on line 4—4 in Fig. 3, parts being omitted;

Fig. 5 is an enlarged detail sectional view, taken as on line 5—5 in Fig. 4;

Fig. 6 is a detail sectional view, taken as on line 6—6 in Fig. 5;

2

Fig. 7 is an enlarged plan view of a fragment of a continuous or endless tape of the station selector;

Fig. 8 is a detail sectional view of the continuous or endless tape disclosing the manner of removably assembling stop plugs or members with said tape; and

Fig. 9 is a wiring diagram of circuits of a station selector incorporating features and characteristics of the invention.

The station selector herein illustrated and described can be employed in connection with any type of radio receiver. In Fig. 2 of the drawings 15 a radio receiver consisting of an antenna 10, a frequency convertor 11, a high frequency oscillator 12, an intermediate frequency amplifier 13, a second detector 14, an audio amplifier 15 and a speaker 16 is disclosed. Also in said Fig. 2 are disclosed circuits of the station selector of 20 the invention, including an antenna 17, a frequency convertor 18 and a high frequency oscillator 19.

Parts of the radio receiver shown in Fig. 2 are housed in a rectilinear box which is designated 25 20 in Fig. 1. A turn button 21 adjacent said rectilinear box 20 is for adjusting the radio receiver to "off," "automatic" or "manual" position, a usual turn button 22 is for tuning in the radio receiver when the turn button 21 is in "manual" 30 position, and a usual turn button 23 is for controlling volume of said radio receiver.

Parts of the station selector shown in said Fig. 2 are housed in a rectilinear box indicated 24 in Fig. 4, and said rectilinear box 24 is housed 35 in a larger rectilinear box, indicated 25, which also contains additional elements of said station selector.

The rectilinear box 25 includes a base wall 26, end walls 27, 27, side walls 28, 28 and an upper wall 29. The upper wall 29 hingedly supports an L-piece 30, constituted as a part of said upper wall and a part of a side wall 28, adapted to be swung to open position thus to afford access to the interior of said rectilinear box 25.

45 A continuous or endless tape 31 of any material suitable to its purpose is supported upon and rideable over idler pulleys 32 which are in turn mounted upon a frame 33 suitably and conveniently supported within the rectilinear box 25. 50 The continuous or endless tape 31 is suitably and conveniently tensioned, as by coil springs 34 attached to said rectilinear box 25 and to some of the idler pulleys 32.

Said continuous or endless tape 31 also rides 55 upon a driven feed pulley 35, and said driven

feed pulley includes two spaced apart sets of spaced apart feed pins 36. The feed pins 36 of each set are adapted to enter spaced apart feed perforations 37 adjacent each of the opposite side edges of the continuous or endless tape 31. The driven feed pulley 35 is fixedly supported upon a horizontal shaft 38 which is suitably and conveniently rotatably mounted upon the frame 33 and fixedly carries a large gear 39.

A synchronous motor 40, suitably and conveniently supported within the rectilinear box 25 and adapted to be energized from any desired source (not shown), includes a driven shaft fixedly supporting a pinion 41 which meshes with teeth 42 upon the periphery of the large gear 39.

The construction and arrangement will be such that the driven shaft of the synchronous motor 40 will make one complete revolution per quarter hour to cause the large gear 39 to make one full revolution in four hours, the driven feed pulley 35 to make one-sixteenth of a revolution each quarter hour, and each transverse line along the length of the continuous or endless tape 31 to accomplish one complete cycle of operation in 168 hours, or one week.

In the disclosure as made, the continuous or endless tape 31 includes spaced apart, transversely extending openings in longitudinally extending rows, denoted 43, 44, 45 and 46, respectively, of equally spaced openings. All of the spaced openings in each of the different longitudinally extending rows 43, 44, 45 and 46 are in aligned relation along the length of the continuous or endless tape 31.

Stop plugs or members 47 are adapted to be removably received in selected ones of the openings of the rows 43, 44, 45, 46 of openings. As will be clear from Fig. 8, each of the stop plugs or members 47 can consist of a shank of stretchable material and a head of solid material. As disclosed at the left in said Fig. 8, the shank of the stop plug or member there shown has been stretched lengthwise thus to be easily insertable in the corresponding tape opening. As disclosed at the right in Fig. 8, the shank of the stop plug or member there shown has been released thus to become expanded and rigidly fastened in the corresponding tape opening. Stated otherwise, the shanks of the stop plugs or members 47 are adapted to be inserted in the tape openings while stretched lengthwise, and released when fully inserted thus to become securely though removably fastened in said tape openings.

The frame 33 pivotally supports, as at 48, an upper arm 49 and lower arms, designated 50, 51, 52 and 53, respectively. In turn, said upper arm 49 supports an insulating panel 54 having spaced apart rows, indicated 55, 56, 57 and 58, respectively, of contact elements, and said lower arms 50, 51, 52 and 53 support insulating panels represented 59, 60, 61 and 62, respectively, each of which supports a row, designated 63, 64, 65 and 66, respectively, of contact elements. The rows 63 and 55, 64 and 56, 65 and 57, 66 and 58, respectively, of contact elements are in vertical alignment.

The construction and arrangement are such that the upper arm 49 is movable upon the pivotal support 48 toward and away from the lower arms 50, 51, 52 and 53, and that said lower arms 50, 51, 52 and 53 are independently movable upon said pivotal support toward and away from said upper arm 49. The construction and arrangement also are such that corresponding contact elements of the rows 63, 55 and 64, 56 and 65,

57 and 66, 58, respectively, can become engaged and disengaged. More explicitly, the row 63 of contact elements includes contact elements denoted 67, 68, 69 and 70 adapted to be engaged with and disengaged from contact elements indicated 71, 72, 73 and 74, respectively, of the row 55 of contact elements, the row 64 of contact elements includes contact elements denoted 75, 76, 77 and 78 adapted to be engaged with and disengaged from contact elements indicated 79, 80, 81 and 82, respectively, of the row 56 of contact elements, the row 65 of contact elements includes contact elements denoted 83, 84, 85 and 86 adapted to be engaged with and disengaged from contact elements indicated 87, 88, 89 and 90, respectively, of the row 57 of contact elements, and the row 66 of contact elements includes contact elements denoted 91 and 92 adapted to be engaged with and disengaged from contact elements indicated 93 and 94, respectively, of the row 58 of contact elements. The contact elements 71, 79, 87 and 72, 80, 88 and 73, 81, 89 and 74, 82, 90 and 93, 94 and 68, 69 and 76, 77 and 84, 85, respectively, are connected together.

25 The driven shaft of the synchronous motor 40, which is adapted to make a complete revolution each quarter hour and fixedly supports the pinion 41 which meshes with the large gear 39, also fixedly supports a cam member 95 in adjacent relation to said pinion 41 and cam members, denoted 96, 97, 98 and 99, respectively, adjacent to the cam member 95 and spaced apart along the length of said synchronous motor driven shaft.

The lower arms 50, 51, 52 and 53 rigidly support extensions, indicated 100, 101, 102 and 103, respectively, which project from said lower arms in direction toward the cam members and away from the pivotal support 48, and said extensions 100, 101, 102 and 103 fixedly support selector elements, designated 104, 105, 106 and 107, respectively, adapted to cooperate in the actuation of the insulating panels 59, 60, 61 and 62 and their rows 63, 64, 65 and 66 of contact elements. In the disclosure as made, each of the selector elements includes a lower feeler pin 108 and an upper retainer lug 109. The feeler pins 108 of the selector elements 104, 105, 106 and 107, respectively, are in alignment with the openings of the rows 43, 44, 45 and 46 of openings in the continuous or endless tape 31, and the retainer lugs 109 of said selector elements 104, 105, 106 and 107, respectively, are adapted to be trapped by and released from the cam members 96, 97, 98 and 99 in a manner to be made plain.

55 Each of said cam members 96, 97, 98 and 99 includes an interior surface 110 of part-cylindrical configuration in concentric relation to the motor shaft upon and over which the retainer lug 109 of the corresponding selector element is adapted to ride, and each cam member 96, 97, 98 and 99 also includes a gap or clearance 111 at one of its sides of width to allow passage of the corresponding retainer lug 109. One end of the part-cylindrical surface 110 of each of the cam members 96, 97, 98 and 99 terminates at one side of the gap or clearance 111 and the other end of the part-cylindrical surface 110 of each cam member 96, 97, 98 and 99 merges in an interior cam surface 112 which curves smoothly outwardly and terminates at the opposite side of said gap or clearance 111.

The cam member 95 includes an exterior surface 113 of part-cylindrical configuration in concentric relation to the motor shaft, a drop-off 75 portion 114 and an exterior cam surface 115 which

curves smoothly outwardly from the interior end of said drop-off portion 114 and merges in said part-cylindrical surface 113. The exterior cam surface 115 is situated at the side of the motor shaft which is diametrically opposite the interior cam surfaces 112.

A supporting bracket 116, rigidly secured to the insulating panel 54, includes a foot portion 117 rideable upon the exterior surfaces 113 and 115 of the cam 95.

Connecting posts between the insulating panel 54 and the insulating panels 59, 60, 61 and 62 are denoted 118, 119, 120 and 121, respectively. Each of said connecting posts has its lower end rigidly connected to an insulating panel, 59, 60, 61 or 62, as the case may be, and its body portion slidably arranged in an opening in the insulating panel 54. A head upon each connecting post is adapted to become engaged with the upper surface of said insulating panel 54 thus to limit the extent to which the insulating panels 59, 60, 61 and 62 can be moved in direction away from the insulating panel 54.

The gaps or clearances 111 of the different cam members 96, 97, 98 and 99 are in alinement in direction longitudinally of the driven shaft of the synchronous motor 40 and the just mentioned cam members and the cam member 95 obviously are adapted to make one complete revolution each quarter hour. The construction and arrangement will be such that the openings of the different rows 43, 44, 45, 46 of openings in the continuous or endless tape 31 will be caused to successively pass beneath the locations of the feeler pins 108 in response to advancement of said continuous or endless tape, and the construction and arrangement also will be such that each of the gaps or clearances 111 will become situated substantially in vertical alinement with each opening of the corresponding row of openings as the openings successively become situated directly below the motor shaft about as disclosed in Fig. 5 of the drawings.

In said Fig. 5, the feeler pin 108 of the selector element 104 is resting upon a stop plug or member 47 in an opening of the row 43 of openings and the feeler pins 108 of the selector elements 105, 106 and 107 are situated in openings of the rows 44, 45 and 46, respectively, of openings. The retainer lug 109 of said selector element 104 is at elevation just above the free end of the interior cam surface 112 of the cam member 96 and alined with said mentioned interior cam surface 112, and the retainer lugs 109 of the selector elements 105, 106 and 107 are situated at elevation below the free ends of the interior cam surfaces 112 of the cam members 97, 98 and 99. The contact elements of the rows 55, 63 of contact elements are interengaged in Fig. 5 and the head of the connecting post 118 is in spaced relation to the upper surface of the insulating panel 54. The contact elements of the rows 56, 64 and 57, 65 and 58, 66 are disengaged in said Fig. 5, and the heads of the connecting posts 119, 120 and 121 are engaged against the upper surface of said insulating panel 54. The foot portion 117 of the supporting bracket 116 is disclosed in Fig. 5 as having just dropped off of the cylindrical surface 113 of the cam member 95.

Supposing the parts of the new and improved mechanism to be situated as in Fig. 5 of the drawings and the synchronous motor shaft to be driven ahead to advance the cam members 95, 96, 97, 98 and 99 in the direction of the arrow in said Fig. 5, the cam surface 112 of the cam member 96 will

become engaged beneath the retainer lug 109 of the selector element 104 thus to cause said selector element 104 to be trapped. With further advancement of said cam member 96, said retainer lug 109 of said selector element 104 will become elevated until the forward portion of the cylindrical surface 110 of the cam member 96 reaches the location of the retainer lug of the selector element 104, and said selector element 104 will remain trapped by said cam member 96 until the cam members have been returned to their positions as in said Fig. 5. At such time, the next succeeding opening in the row 43 of openings will be beneath the selector element 104 and said selector element will become released to be moved downward by gravity. If said next succeeding opening of row 43 of openings has no stop plug or member 47, the feeler pin 108 of the selector element 104 will enter said next succeeding opening, but if the opening mentioned contains a stop plug or member 47, the feeler pin of said selector element 104 will engage said stop plug or member to cause the selector element to be situated as in Fig. 5. With advancement of the cam member 95 the cam surface 115 will ride under the foot portion 117 of the supporting bracket 116 thus to cause the insulating panel 54 to be elevated. At this same time, however, the interior cam surface 112 of the cam member 96 will cause the insulating panel 59 to be elevated an equal amount, or to the same degree, thus to cause the contact elements of rows 55 and 63 of contact elements to remain engaged. The construction and arrangement will be such that when the exterior cylindrical surface 113 of the cam member 95 commences to ride under the foot portion 117 as the cam surface 115 rides from under said foot portion, the interior cylindrical surface 110 of a cam member 96, 97, 98 or 99, as the case may be, will commence to ride under the retainer lug 109 of the corresponding selector element as the cam surface 112 rides from under the retainer lug of said selector element. Stated otherwise, the construction and arrangement will be such that rows 55, 63 or 56, 64 or 57, 65 or 58, 66 of contact elements caused to become engaged because of the feeler pin 108 of the corresponding selector element becoming engaged against a stop plug or member 47, as the rows 55, 63 of contact elements are disclosed in Fig. 5 of the drawings, will remain engaged for the whole of a quarter hour. The exterior cylindrical surface 113 will pass from under the foot portion 117 at the same instant that the interior cylindrical surface 110 passes from under the retainer lug 109 of a trapped selector element. Also with advancement of the cam member 95 from its position as in Fig. 5, and riding of the cam surface 115 under said foot portion 117 of the supporting bracket 116 to cause the insulating panel 54 to be elevated, any feeler pins 108 in openings in the continuous or endless tape in said Fig. 5 will be removed from said tape through the instrumentality of the corresponding connecting posts, as will be obvious. That is to say, the heads of the connecting posts engaged with the insulating panel 54 in Fig. 5 will be elevated in response to elevation of said insulating panel 54, thus to cause the insulating panels which are rigid with said connecting posts to be elevated and the feeler pins 108 of the corresponding selector elements to become removed from the tape openings. Feelers pins removed from tape openings will be held above the tape until the foot portion 117 falls from the drop-off 114 and will then drop either

to enter other openings or to engage stop plugs or members 47, as the case may be.

In Fig. 9 of the drawings, 122 denotes a loop antenna, 123 indicates a high frequency oscillator coil, 124 designates a pentagrid convertor tube including a heater 125, and 126 represents a radio frequency choke. Pretuned variable condensers are designated 127, 128, 129, 130, 131 and 132.

An intermediate signal conducting connection 133 extends to the loop antenna 122, a conducting connection 134 extends from said loop antenna to a grid of the convertor tube 124, and an intermediate signal conducting connection 135 extends from said convertor tube.

The radio frequency choke 126 is connected between the conducting connection 135 and grids of the convertor tube 124, as well as between the conducting connection 133 and said conducting connection 135.

A conducting connection 136 extends from the conducting connection 134 to the contact element 90, conducting connections 137 extend from the conducting connection 133 to each of the variable condensers 127, 128, 129, 130, 131 and 132, and conducting connections, denoted 138, 139, 140, 141, 142 and 143, respectively, extend from said variable condensers to the contact elements 70, 78, 86, 67, 75 and 83.

The high frequency oscillator coil 123 is connected between the conducting connection 133 and a grid of the convertor tube 124, as well as between said conducting connection 133 and the radio frequency choke 126.

Conducting connections to the heater 125 are denoted 144 and 145, and power circuit conducting connections to the contact elements 72 and 73 are indicated 146 and 147, respectively.

The contact elements 91 and 92 are included in a circuit also including a motor 148 adapted to be energized by a battery 149.

The circuits included in Fig. 9 of the drawings also incorporate resistances, fixed condensers, etc., which are requisite to the proper and intended functioning of said circuits.

The mechanism as herein illustrated and described is adapted to be capable of selecting any desired one of three different radio stations to which the radio receiver disclosed is to be tuned, and said mechanism also is capable of selectively causing the circuit including the motor 148 to be closed and opened. It will be apparent that the embodiment of the mechanism selected for illustration and description is adapted to be set up for operations each continuing for a quarter hour interval throughout a period of a week, and that at the end of a week's performance the operations of said mechanism will be repeated.

A stop lug or member 47 in any opening of row 43 of openings is adapted to cause the contact elements of rows 55 and 63 of contact elements to be interengaged and held interengaged for a quarter hour, in the manner as hereinbefore set forth, and interengagement of said rows 55 and 63 of contact elements will cause one of the several radio stations which are capable of being selected, say radio station A, to be tuned into the radio receiver. The selection of radio station A obviously will be a function of tank circuits of Fig. 9 of the drawings including the loop antenna 122, the pretuned variable condenser 127, the high frequency oscillator coil 123, the pretuned variable condenser 130, etc. Stated otherwise, tank circuits of said Fig. 9 adapted to be closed when the rows 55 and 63 of contact elements become interengaged include variable condensers 127 and 130

so pretuned as to cause a particular value adapted to select the frequency emanating from said radio station A to be resonated and the audio signal received to be imparted to the intermediate frequency amplifier of the radio receiver.

A stop plug or member 47 in any opening of row 44 of openings is adapted to cause the contact elements of rows 56 and 64 of contact elements to be interengaged for a quarter hour, and interengagement of said rows 56 and 64 will cause a different one of the radio stations, say radio station B, to be tuned in. The selection of radio station B will be a function of tank circuits including the loop antenna 122, the pretuned variable condenser 128, the high frequency oscillator coil 123, the pretuned variable condenser 131, etc. That is to say, tank circuits adapted to be closed when the rows 56 and 64 of contact elements become interengaged include variable condensers 128 and 131 so pretuned as to cause a particular value adapted to select the frequency emanating from said radio station B to be resonated and the audio signal received to be imparted to the intermediate frequency amplifier of the radio receiver.

A stop plug or member 47 in any opening of row 45 of openings is adapted to cause the contact elements of rows 57 and 65 of contact elements to be interengaged for a quarter hour, and interengagement of said rows 57 and 65 will cause a yet different one of the radio stations, say radio station C, to be tuned in. The selection of radio station C will be a function of tank circuits including the loop antenna 122, the pretuned variable condenser 129, the high frequency oscillator coil 123, the pretuned variable condenser 132, etc. Put differently, tank circuits adapted to be closed when the rows 57 and 65 of contact elements become interengaged include variable condensers 129 and 132 so pretuned as to cause a particular value adapted to select the frequency emanating from said radio station C to be resonated and the audio signal received to be imparted to the intermediate frequency amplifier of the radio receiver.

It will be evident that the continuous or endless tape 31 could include additional rows, such as 43, 44, 45, of openings adapted to receive stop plugs or members, such as 41, for causing other tank circuits including pretuned variable condensers, such as 127, 130 and 128, 131 and 129, 132, to be closed and opened, thus to cause additional radio stations to be selectively tuned in.

A stop plug or member 47 in any opening of row 46 of openings is adapted to cause the contact elements of rows 58 and 66 of contact elements to be interengaged for a quarter hour, and interengagement of said rows 58 and 66 will cause the circuit including the motor 148 to be closed. Said motor 148 can be employed for any desired purpose, as, for instance, to actuate or drive a phonograph.

Also it will be evident that the continuous or endless tape 31 could include additional rows, such as 46, of openings adapted to receive stop plugs or members, such as 41, for causing circuits additional to the circuit including the motor 148 to be closed and opened.

What is claimed is:

1. In a mechanism for selectively closing and opening electric circuits, an upper contact element mounted for movement in vertical direction, a lower contact element mounted for movement in vertical direction adapted to be engaged with and disengaged from said upper contact

element, a supporting member rigid with said upper contact element, a selector element rigid with said lower contact element and having a retainer element, a first cam member ridable beneath said supporting member including an exterior part-cylindrical surface, a drop-off portion extending interiorly from said exterior part-cylindrical surface and an exterior cam surface curving smoothly outwardly from the interior end of said drop-off portion and merging in said exterior part-cylindrical surface, and a second cam member for trapping and releasing said retainer element including an interior part-cylindrical surface in concentric relation to said exterior part-cylindrical surface, there being a clearance situated opposite said drop-off portion and an interior cam surface opposite said exterior cam surface curving smoothly outwardly from said interior part-cylindrical surface and terminating at said clearance.

2. In a mechanism for selectively closing and opening electric circuits, an upper contact element mounted for movement in vertical direction, a lower contact element mounted for movement in vertical direction adapted to be engaged with and disengaged from said upper contact element, a supporting member rigid with said upper contact element, a selector element rigid with said lower contact element and having a feeler pin and a retainer element, a first cam member ridable beneath said supporting member including an exterior part-cylindrical surface, a drop-off portion extending interiorly from said part-cylindrical surface and an exterior cam surface curving smoothly outwardly from the interior end of said drop-off portion and merging in said exterior part-cylindrical surface, a second cam member for trapping and releasing said retainer element including an interior part-cylindrical surface in concentric relation to said exterior part-cylindrical surface, there being a clearance situated opposite said drop-off portion and an interior cam surface opposite said exterior cam surface curving smoothly outwardly from said interior part-cylindrical surface and terminating at said clearance, a member having spaced apart openings adapted to removably receive stop members, means for feeding said member to cause said spaced apart openings to be successively situated beneath said feeler pin, and a connecting post between said upper and lower contact elements rigid with the lower contact element and slidable relative to the upper contact element.

3. In a mechanism for selectively closing and opening electric circuits, an upper contact element mounted for movement in vertical direction, a lower contact element mounted for movement in vertical direction adapted to be engaged with and disengaged from said upper contact element, a supporting member rigid with said upper contact element, a selector element rigid with said lower contact element and having a retainer element, a first cam ridable beneath said supporting member including an exterior part-cylindrical surface, a drop-off portion extending interiorly from said exterior part-cylindrical surface, and an exterior cam surface curving smoothly outwardly from the interior end of said drop-off portion and merging in said exterior part-cylindrical surface, and a second cam member for trapping and releasing said retainer element including an interior part-cylindrical surface in concentric relation to said exterior part-cylindrical surface, and an interior cam surface opposite said exterior cam surface curving smoothly outwardly from said interior part-cylindrical surface and terminating at a clearance situated opposite said drop-off portion.

drical surface and an exterior cam surface curving outwardly from the interior end of said drop-off portion and merging in said exterior part-cylindrical surface, and a second cam member for trapping and releasing said retainer element including an interior part-cylindrical surface in concentric relation to said exterior part-cylindrical surface and an interior cam surface opposite said exterior cam surface curving outwardly from said interior part-cylindrical surface and terminating at a clearance situated opposite said drop-off portion.

4. In a mechanism for selectively closing and opening electric circuits, an upper contact element mounted for movement in vertical direction, a lower contact element mounted for movement in vertical direction adapted to be engaged with and disengaged from said upper contact element, a supporting member rigid with said upper contact element, a selector element rigid with said lower contact element and having a feeler pin and a retainer element, a first cam member ridable beneath said supporting member including an exterior part-cylindrical surface, a drop-off portion extending interiorly from said part-cylindrical surface and an exterior cam surface curving outwardly from the interior end of said drop-off portion and merging in said exterior part-cylindrical surface, a second cam member for trapping and releasing said retainer element including an interior part-cylindrical surface in concentric relation to said exterior part-cylindrical surface and an interior cam surface opposite said exterior cam surface curving outwardly from said interior part-cylindrical surface and terminating at a clearance situated opposite said drop-off portion, a member having spaced apart openings adapted to receive stop members, means for feeding said member to cause said spaced apart openings to be successively situated beneath said feeler pin, and connecting means between said upper and lower contact elements rigid with one of the contact elements and movably assembled with the other contact element.

EARL H. PITNEY.
